UNITED STATES PATENT OFFICE.

GEORGE W. STAFFORD AND HENRY BARKER, OF LAWRENCE, MASS.

JACQUARD ATTACHMENT FOR LOOMS.

SPECIFICATION forming part of Letters Patent No. 236,375, dated January 4, 1881.

Application filed June 28, 1880. (No model.)

To all whom it may concern:

Be it known that we, GEORGE W. STAFFORD, a citizen of the United States, and HENRY BARKER, a subject of Great Britain, both residing at Lawrence, in the county of Essex and State of Massachusetts, have invented certain new and useful Improvements in Jacquard Attachments for Looms; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to close-shed looms provided with a Jacquard attachment; and it consists in means for depressing a portion of the warp-threads below the warp-level at the same time that the warp-threads needed for the pattern are raised above the said level—in other words, obtaining in a jacquard the result with the series of single or independent threads that is effected by the ordinary open-shed loom with a harness-frame, the purpose of the invention being to lessen the tension and friction upon the warp, reduce the cost of the engine, and enable the loom to be driven at greater speed.

The drawings accompanying this specification represent, in Figure 1, an isometric elevation of a shedding-engine or Jacquard attachment, while Fig. 2 is a vertical section of the frame.

In these drawings, A represents the frame of the engine or attachment, the same being composed of upright side standards or housings, B B, united by horizontal cross-beams or bars C C, &c., while the guide-plate, which directs the lower ends of the harness or drop wires and spans the area between the housings B B, is shown at D.

The horizontal "needles," as they are termed, of the two ranges are shown at a a, &c., and b b, &c., their retracting-springs at b' b', &c., and their eyes at c c, &c., while the vertical hooks or drop-wires of the two ranges are shown at d d, &c., and e e, &c., respectively.

The pattern-cylinder is omitted from the drawings; but the needle-plate with which such cylinder operates is shown at E as se-

cured to the upper front part of the housings B B. The warp-threads are shown at f f, &c., the harness or neck-cords connected to the lower ends of the hooks at g g, &c., and the "mails" of said cords at i' i', &c.

The above embrace the elementary features of a Jacquard attachment now in general use.

In carrying out our invention we employ a horizontal open rectangular frame, F, arranged between the upper parts of the housings B B, and with its end bars secured to vertical rods j j, which slide in bearings k k in the contiguous faces of said housings, the frame being thus adapted to slide vertically upon its supports with respect to the other portions of the machine, and carrying upon opposite sides horizontal parallel rods or bars l l, from which the hooks are suspended.

The alternating vertical movements of the frame or carrier F are effected by a mechanism consisting as follows: The lower end of a vertical rod, m, is pivoted centrally to the frame, such rod extending upward through a slot in the upper cross-bar, C, of the machine-frame, and being pivoted at its upper end to the inner extremity or arm, n, of a horizontal lever, o, such lever being fulcrumed, as shown at p, to an arm, q, erected upon one end of the said bar C, and at its outer end being pivoted to the upper end of a second rod, r, the lower end of which, in turn, is pivoted to the knee s of a toggle-jointed lever, t u, which is added to the outside of the housing and below the plane of the lifting-frame F, the support of the upper arm, t, of the toggle being a bracket, v, secured to the housing. The lower support of the toggle is a bracket, w, erected upon one end of the guide-plate D, before named; and this guide-plate, in lieu of being rigidly secured to the frame of the engine and serving simply as a guide to the lower ends of the drop-wires, is in this instance supported in position upon the housings by guides or ways y y, which permit it to rise and fall, and these movements are imparted by the toggle-jointed lever before named, while the rise and fall of the carrier-frame F are effected by the lever o, the arrangement of parts being such that the frame and guide-plate move in opposite directions.

To sustain the plate D in a horizontal position and insure its correct movement, we add

to the opposite side of the engine a duplicate of the mechanism last explained, the second horizontal lever being shown at a' , the toggle-jointed lever at $b'' c''$, its supports at d' and e' , 5 and the two bars of the lower bracket at $f' g'$.

The lower end of each harness-wire, in lieu of simply playing in a guide within the guide-plate D, is formed with a head or bend, h' , upon the upper end of the shorter portion or 10 side of its eye or loop i , to which the harness-cord is connected, and this head h' of the drop-wire is disposed above the guide-plate and intercepts the latter as it completes its ascent. When the warp is level the guide-plate is in 15 its highest and the carrier-frame in its lowest position, with the heads h' of the drop-wires resting upon the top of the guide-plate, and the latter thus serving to uphold such wires and lift their upper hooked ends, k' , out of engagement with the suspensors $l l$, and so that upon the incoming of the pattern cylinder and card the wires not needed for the pattern are 20 pushed inward beyond the path of movement of the suspensors, while those required for 25 the pattern remain in a position to be engaged by such suspensors when the latter rise.

The levers o and a' derive motion from the crank-shaft of the loom through a connecting-rod or pitman, as shown in Fig. 1. 30 The operation of the above-described mechanism is briefly as follows, it being understood that the frame F is in its lowest and the plate D in its highest position, with the pattern cylinder and card about to come in and with the warp level: The cylinder and card move in, 35 and by pushing in a portion of the needles leave free a portion of the drop-wires. The pattern cylinder and card move in at the same time that frame F and guide-plate D move toward each other, so that when the pattern-card 40 strikes the needles the hooks are clear of the suspensors $l l$. The carrier-frame with its rods or suspensors $l l$ now begin to rise to

meet the hooks of the drop-wires, and the drop-wires by and with the guide-plate begin simultaneously to descend until the said hooks engage the rods, when the frame and plate complete their respective movements, the result being that the frame in its ascent carries with it and elevates above the warp-level such drop-wires and warp-threads as are needed for the pattern, while the other wires and warp-threads drop with the guide-plate below the warp-level. The shuttle passes through the warp and returns, and the carrier-frame and guide-plate 45 now reverse their movements and return to the positions first named, the warp-threads also returning to a common level, the pattern cylinder and card retreat, and the drop-wires return to one plane in readiness for the next ensuing 50 incoming of the pattern card and cylinder.

It will be seen that by moving the warp-threads in opposite directions to admit the shuttle, in lieu of a movement in one direction of double the distance, we avoid to a corresponding degree the stretch or tension of the warp-threads. We are also enabled to simplify the construction of the engine and to attain a higher 55 rate of speed of the loom.

The operating-levers of the frame and guide-board may be actuated by any suitable motor.

We claim—

The combination, with a vertically-movable guide board or plate, a lifting frame, and sets of hooks and needles, of a pair of levers, the suspending-rod of said frame, and the rods and toggles for depressing and raising said guide-plate, substantially as described.

In testimony whereof we affix our signatures in presence of two witnesses.

GEORGE W. STAFFORD.
HENRY BARKER.
